(57) **CLAIM**

The ornamental design for the “measurement instrument,” as shown.

DESCRIPTION

FIG. 1 is a front elevational view of a first embodiment of the measurement instrument showing our new design;

FIG. 2 is a top plan view thereof;

FIG. 3 is a left side elevational view thereof;

FIG. 4 is a right side elevational view thereof;

FIG. 5 is a rear elevational view thereof; and,

FIG. 6 is a bottom plan view thereof.

The broken line shown in FIG. 3 is for illustrative purposes only and forms no part of the claimed design.
